UNITED STATES PATENT OFFICE.

JOHN BROWN NIXON, OF BUTLER, PENNSYLVANIA.

CARD HOLDER.

Application filed October 17, 1927. Serial No. 226,576.

My invention relates more particularly to card holders for supporting hotel and restaurant menu cards and the like, and which may also be employed for supporting newspapers, 5 etc.

One object of my invention is to provide various features in combination with a card holder which will render it especially useful in dining rooms.

10 Another object of my invention is to provide a combined card holder and ash tray in such manner that access to the tray will not be obstructed by the holder or a card supported thereby, and wherein the tray is so located 15 and of such form that it will support a card or newspaper against falling from an inclined position.

One form which my invention may take is shown in the accompanying drawing, where- 20 in Figure 1 is a perspective view of a holder embodying my invention; Fig. 2 is a side ele- vational view thereof; Fig. 3 is a perspective view of the ash receptacle of Fig. 1, and Figs. 4 and 5 are views taken on the lines IV—IV 25 and V—V respectively of Fig. 1.

The main portion of the holder is composed of a base or body portion 6 having a rear- 30 ward extension 7, wing portions 8, an inclined back rest 9 and match receptacles 10 and 11. The parts just enumerated are shown as integrally formed and as cast from vitreous material, such as glass or porcelain, but the holder may be formed of other mate- 35 rials and its parts suitably assembled. The body portion 6 is also recessed for the recep- 40 tion of an ash holder 12 that may be conven- iently removed for cleaning, and which is provided with a centering boss or lug 13 (Fig. 4) that extends into a recess in the base 6. The ash receptacle 12 is intended to receive ashes, stubs, etc., and is also provided with curved recesses 14 for supporting partially consumed cigars or cigarettes, and with a recess 15 wherein cigarettes may be snuffed. 45

The back rest 9, being inclined, serves as a convenient support for a menu card, news- 50 paper, book, or the like, and the weight of the base portion 6 serves to prevent tilting of the holder under the weight of the reading matter. The wing portions 8 serve as braces 50 to assist in avoiding backward tilting of the holder and also add a pleasing appearance to the device.

The card or newspaper is held against tilt- 55 ing backward, even though it may be of con- siderably greater height than the back rest 9 by reason of the fact that its lower edge will be supported in the channel at the lower front edge of the back rest. As an additional pre- 60 caution against tilting of the larger articles supported by the back rest, I provide an aux- 65 illary supporting member 16 which may be formed of stiff wire or a metal rod, and whose ends are inturned to extend into the exten- 70 sion 7, the holder 16 being supported in in- clined position by lugs 17 on the ends of the back rest 9. The ends of the holder 16 may be readily sprung into and out of place, so that it can be readily removed or applied when desired.

The term "ash tray" is employed here in its broad sense as including not only a receptacle for ashes, but perhaps also match holders, etc., such as are commonly associated therewith.

75 I claim as my invention:—

1. A holder comprising a body member, a back rest connected to a rear portion thereof and extending upwardly, wing members connected to the vertical edges of the back rest, 80 and an auxiliary supporting member detach- ably connected to the body member and sup- ported by the said wing members in inclined position.

2. A holder comprising a body member, 85 a back rest connected to the rear portion thereof and extending upwardly, wing mem- bers connected to the vertical edge of the back rest, and an auxiliary supporting mem- 90 ber detachably connected to the body member and supported by the said wing members in inclined position, the said auxiliary member extending beyond the upper edge of the back rest.

In testimony whereof I, the said JOHN 95 BROWN NIXON, have hereunto set my hand.

JOHN BROWN NIXON.
